UNITED STATES PATENT OFFICE.

ALDEN G. RAYBURN, OF SAUSALITO, CALIFORNIA, ASSIGNOR TO EMORY WINSHIP, OF SAN FRANCISCO, CALIFORNIA.

DOOR OPENER.

Application filed August 4, 1923. Serial No. 655,638.

The invention relates to door openers and particularly to means for opening the doors of a vehicle such as a street car.

An object of the invention is to provide a street car door, which when opened will not interfere with the movement of passengers to and from the car.

Another object of the invention is to provide a street car door which, in its opening or closing movement, occupies a minimum of space so that the passengers will not be compelled to move to provide space to permit the door to move.

Another object of the invention is to provide a street car door of the type described which may be readily opened by the operator of the vehicle.

The invention possesses other advantageous features, some of which with the foregoing, will be set forth at length in the following description, where I shall outline in full, that form of my invention which I have selected for illustration in the drawings accompanying and forming part of the present specification. In said drawings I have shown one form of device for opening the doors, but it is to be understood that I do not limit myself to such form, since the invention, as set forth in the claims, may be embodied in a plurality of forms.

Referring to said drawings:

Figure 1 is a horizontal section through a portion of a street car showing the doors and door opening means of my invention.

Figure 2 is an elevation of a portion of the street car showing the doors closed.

Figure 3 is a section taken on the line 3—3 Figure 1.

Figure 4 is a diagrammatic plan view of an internal combustion engine propelled street car showing the device of my invention in its environments.

The device of my invention is particularly adapted to be used on motor busses or internal combustion engine driven street cars, which are operated by one man. In street cars, or motor busses, it is advisable that the doors may be opened and closed without swinging through a space which may be occupied by passengers. The doors may not swing outward and if they swing inward they may require too much room for their opening or closing movement. In accordance with my invention I have provided doors, which in their movement will not in-

terfere with the passengers. Further, the construction of vehicles of this character is such that the doors may not slide, while maintaining parallelism, since the door is usually arranged at the end of the vehicle and if moved in one direction only, would project from the end of the vehicle. In accordance with my invention the spread of the doors is substantially the same when they are closed or open.

In Figure 4 I have illustrated diagrammatically the plan of a vehicle of this character, showing the doors disposed at one end of the vehicle. The vehicle body is provided with an opening 4 which is closed by the doors 5, 6. The doors are mounted on a track having a straight portion 7 extending across the opening 4 and straight portions 8 and 9 lying at opposite sides of the opening and preferably arranged parallel and extending backward from the opening. The straight portion 7 of this track is connected to the straight portions 8 and 9 by the curved portions 12 thus forming a continuous track having central and terminal straight portions, connected by intermediate curved portions. The doors 5 and 6 are mounted on the track, each door being preferably provided with a hanger 13 at each end, the hangers being swiveled to the doors so that they may oscillate as they pass over the curved portion of the track. The doors are also preferably provided at the bottom with a guideway 14 having the same shape as the track, so that the doors are guided at the top and bottom. As the doors are opened or closed they swing through paths at the sides of the opening and thereby do not interfere with passengers standing on the platform adjacent the opening or standing on the street.

Means are provided for simultaneously moving both doors in opposite directions so that the opening may be readily closed or opened. Fulcrumed to a fixed portion of the structure of the vehicle, are two levers 16 and 17 having slotted ends, in which engaged pins 19 are preferably disposed in alignment with one of the hangers. A spring 21 is preferably disposed in the slotted portion of each lever between the end of the slot and the pin to insure proper movement of the door with respect to the lever. Means are provided for connecting the levers together so they move simultaneously in oppo-

site directions. Each lever is provided with an arcuate rack 22, the two racks being in mesh so that the levers move simultaneously and oppositely. These levers may be arranged below the floor 23 of the vehicle or they may be arranged above the ceiling 24 of the vehicle or they may be arranged in both places, as shown in Figure 3.

Means are provided for moving the levers from a remote point, for instance from the driver's seat, so that the driver may have full control of the door opening. The lever 17 is provided with an arm, to which is connected a rod 25 which is connected at its other end to a lever 26. The other end of the lever 26 is connected to a rod 27 which in turn is connected to the hand operated lever 28 which is preferably disposed adjacent the driver's seat. Movement of the lever 28 is thus transferred to the levers 16 and 17 and doors are thus simultaneously moved to the open or closed position. The lever 26 is fulcrumed on a rod 29 and when it is desirable to arrange the door moving levers both below and above the door as is shown in Figure 3, the rod 29 extends upward through the partition 31 and one set of door opening levers is arranged on the upper end of the rod and another set of the door opening levers is arranged on the lower end of the rod. This provides a balance and prevents any possible jamming of the doors. The doors may thus be readily opened and when opened provide a clear passageway for the passengers, and in their opening and closing movement, do not interfere with passengers standing on the platform or desiring to board the vehicle. In the present construction the pins extend through slots in the tracks and consequently must be arranged in alinement with the hangers. When however, the pins do not extend through the tracks, the pins may be arranged at any desired positions in the edges of the doors.

45 I claim:

1. A device of the character described comprising upper and lower tracks each having a portion extending across an entrance opening and a portion extending laterally of said opening, said portions being joined by a curved portion, a movable closure engaging said tracks at its upper and lower ends and adapted to close said opening in one position, a horizontal lever having a pivoted mounting above said entrance and engaging the upper end of said closure, a horizontal lever having a pivotal mounting below said entrance and engaging the lower end of said closure, an actuating lever having a pivotal mounting to one side of said entrance, and means connecting said actuating lever with both upper and lower levers whereby upon movement of said actuating lever both the upper and lower ends of said closure are moved to slide said clo-

sure on said tracks, said entrance being substantially unobstructed when said closure is moved to an out of the way position.

2. A device of the character described comprising upper and lower tracks each having a portion extending across an entrance opening and a portion extending laterally and to one side of said entrance opening, said portions being joined by a curved portion, a movable closure engaging said tracks at its upper and lower ends and adapted to close said opening in one position, a lever having a pivotal mounting above said entrance and engaging the upper end of said closure, a lever having a pivotal mounting below said entrance and engaging the lower end of said closure, a vertical shaft pivotally mounted to one side of said entrance and having an actuator lever mounted upon each end of the same, means for linking together said actuator levers with said first named levers whereby rotation of said vertical shaft effects a movement of said closure to an out of the way position or to a closed position, said entrance being substantially unobstructed when said closure is moved to open position.

3. A device of the character described comprising upper and lower tracks each having a central portion extending across an opening and side portions extending laterally of said opening, said portions being joined by curved portions, a pair of movable closures having their upper and lower ends engaged by said tracks and adapted to close said opening in one position, a pair of horizontal levers pivotally mounted above said opening and engaging the upper ends of said closures, a corresponding pair of horizontal levers pivotally mounted below said opening and engaging the corresponding lower ends of said closures, an actuating lever pivotally mounted to one side of said opening, means mechanically connecting said actuating lever with one lever of each of said pairs of levers, and means connecting the levers of each pair whereby they are constrained to move oppositely in synchronism upon movement of said actuator lever to move said closure members to an out of the way position or to a closed position, said opening being substantially unobstructed when said closures are moved to an out of the way position.

4. A device of the character described comprising upper and lower tracks each having portions extending laterally across a passageway, a pair of movable closures having their upper and lower ends engaged by said tracks and adapted to close said passageway in one position, a pair of levers having pivotal mountings above said passageway and engaging the upper ends of said closures, a corresponding pair of levers having pivotal mountings below said pas-

sageway and engaging the corresponding lower ends of said closures, an actuating lever having a pivoted mounting to one side of said passageway, means mechanically connecting said actuating lever with said pairs of levers, and means connecting the levers of each pair whereby they are constrained to move oppositely in synchronism upon movement of said actuating lever to move

said closures to an out of the way position 10 or a closed position, said passageway being substantially unobstructed when said closures are moved to an out of the way position.

In testimony whereof, I have hereunto 15 set my hand.

ALDEN G. RAYBURN.
